UNITED STATES PATENT OFFICE.

CHARLES D. LANNING AND EDGAR F. HATHAWAY, OF DORCHESTER, MASSACHUSETTS,
ASSIGNORS TO AMERICAN WARP DRAWING MACHINE COMPANY, OF BOSTON,
MASSACHUSETTS, A CORPORATION OF MAINE.

MACHINE FOR OPERATING UPON WARP-THREADS.

1,147,412.

Specification of Letters Patent.

Patented July 20, 1915.

Application filed June 25, 1906. Serial No. 323,214.

To all whom it may concern:

Be it known that we, CHARLES D. LANNING and EDGAR F. HATHAWAY, both citizens of the United States, and residing at

5 Dorchester, in the county of Suffolk and State of Massachusetts, have invented an Improvement in Machines for Operating upon Warp-Threads, of which the following description, in connection with the accompanying drawings, is a specification, like letters on the drawings representing like parts.

10 Our invention relates to machines for operating upon warp threads, the same being herein embodied in a warp-uniting machine.

15 Our invention will be best understood by reference to the following description when taken in connection with the accompanying illustration of one specific embodiment thereof, while its scope will be more particu-

20 larly pointed out in the appended claims.

In the drawings,—Figure 1 is a front elevation, partially broken away, of a machine embodying one form of our invention; Fig. 2 is an end elevation of the same looking 25 from the left in Fig. 1; Fig. 3 is a similar view looking from the right in Fig. 1; Fig. 4 is an end elevation on an enlarged scale, showing the upper portion of the warp compensating mechanism; Fig. 5 is an end elevation, partly in section, of the lower portion of said mechanism; Fig. 6 is a similar view showing the parts in a different relation; Fig. 7 is a plan view showing a portion of the two pairs of lease rods and the sleeves 30 thereon; Fig. 8 is a sectional view of the lease rods and their sleeves, showing the relation of the leased threads thereto, and Fig. 9 is a detail. Fig. 10 is a detail showing locking means for the manual compensating 35 device.

40 Referring to the drawings, we have there illustrated our invention by showing the same embodied in one specific form of machine which comprises a thread or warp-uniting machine employing a thread-twisting mechanism for twisting together the thread ends of the warp.

45 The machine illustrated has supporting legs a, a , upon which are mounted the standards a', a' . The two legs are joined by the two rods a^2 , upon which is mounted for sliding movement the warp-uniting carriage

A. The standards are also joined by the two rods a^3 , over which the warp threads are drawn when the warp is placed in the machine. 55

Each warp is mounted upon the machine for longitudinal adjustment relatively both to the uniting mechanism and the remaining warp by means of suitable warp holders or 60 carriages, the same comprising in each case the end frame members b , united by the upper and lower rods b', b^2 , and having at each end a pair of outwardly projecting hanger rods b^3 supported in the frame upon roller 65 supports b^4 , and also a similar pair of overhead hanger rods b^5 , slidable in suitable recesses in the standards a' . This permits within certain limits a free adjustment of each warp support or carriage lengthwise 70 of the machine.

To the lower carriage rod b^2 upon each support is fastened a pair of inwardly projecting brackets b^6 , (Fig. 2) provided with clamping jaws b^7 in which is fastened the 75 clamp bar which clamps the ends of the warp threads. To the rod b' of each carriage is loosely secured a pair of upwardly extending arms or brackets b^8 , carrying clamping jaws b^9 in which is secured the 80 second clamping bar, the arms b^8 being secured to fixed arms b^{8x} of the carriage by tension springs b^{10} , through which they are drawn against adjustable stop screws b^{11} . This permits the desired tension to be placed 85 upon the threads of the warp.

Each warp before being placed in the machine is leased by the two sets of lease rods c, c' and d, d' , to be more fully described, and, with its ends clamped in the end or 90 lower clamping bar is led into the machine over the channel iron of the upper clamping bar and the rod a^3 , and thence downward where the clamping bar is clamped in the lower clamping jaws b^7 . The lease rods are 95 then placed in position in the end supports and the upper clamping bar inserted in its channel iron b^{9x} to clamp the threads in position. Both warps when in position have the general relation shown by the dotted 100 lines, (Figs. 2 and 3), where they are in a general parallel relation although the separate sets are individually spread and separated by the lease rods.

Although any suitable movement may be given the related parts, in the illustrated machine, the warp supports, save for the compensating or adjusting feed to be described, are held stationary and the twisting mechanism is caused to advance endwise toward the foremost threads at the extreme side of the warps and act thereon:

The twisting mechanism which is mounted upon the traveling carriage A is constantly fed forward by the lead screw shaft *e* with which engages a split nut A' on the carriage, disengagement of the nut being controlled by the cam A² (see Fig. 1). The lead screw 10 may be turned by the hand crank *e'*, for hand adjustment of the twisting carriage, but during operation of the machine it is driven from the main drive shaft *f* through change speed gearing supported upon the arm *f'* 15 swingingly mounted for adjustment about the drive shaft *f* at one end of the machine (Fig. 3). The drive shaft carries the driving pinion *f²*, meshing with the intermediate pinion *f³* journaled on the swinging arm. 20 The pinion *f³* drives a similar pinion *f⁴*, the latter engaging with the larger gear *f⁵*, journaled in a bearing adjustably clamped in a slot in the swinging arm. The gear *f⁵* turns the smaller pinion *f⁶*, mounted co-axially 25 therewith, the latter meshing with the gear *e²* upon the end of the lead screw *e*.

The drive shaft is driven through the pulley *f⁷* at its opposite end from any suitable source of power. When it is desired to 30 change the speed of rotation of the lead screw to alter the rate of advance of the twisting mechanism, the gears *f⁴* and *f⁵* upon the swinging arm may be replaced by other gears of a size suited to give the desired speed transmission, the arm *f'* being adjusted to the proper position and there clamped by means of the clamping arm *f⁸* the shank for which passes through a curved slot in the arm *f'*.

In practice the two warps are seldom of the same width, the one taken from the loom usually being narrow and having a closer thread spacing than the other and some compensation for this difference must 45 be made to maintain the necessary measure of alinement between the uniting mechanism and the individual threads of each warp. While each set of warp threads may be adjusted relatively to the advance of the uniting mechanism, if desired, either automatically or by hand, in the present machine we prefer to proportion the advance of the uniting mechanism with reference to the spacing or width of one warp,—and herein 50 the narrower one,—and automatically but intermittently impart a slight movement to the remaining warp in a direction opposite to the advance of the uniting mechanism, thereby to maintain the required alinement 55 between the corresponding threads in the 60

two warps. The automatic compensating mechanism is, however, such that it may be placed in operative relation to either warp support at will.

In addition to the automatic compensating mechanism, there is also provided means for manually adjusting either warp relatively to the other or to the uniting mechanism, such manual compensating means being useful to correct localized irregularities in the spacing 75 of the threads.

For the automatic compensating movement the lead screw shaft *e* is provided with the pointed cam *g* (Figs. 5 and 6). Disposed above the shaft *e* and transversely thereof is a slide *h*, having a handle *h'* and provided with a slot *h²*, whereby the slide is permitted longitudinal movement upon the machine frame, being guided in such movement by the pin *h³* projecting from the said frame. Pivoted to said slide are two links, *i*, *i*, having their other ends connected to a cam member *j* through the instrumentality of slots *i'* in said links engaging pins *j'* upon said cam member *j* which has two cam faces *j²* and *j³*. Upon the machine frame, beneath said cam member, are two pins *k*, *k*. Said cam member is disposed above and in the same vertical plane as the pointed cam *g*. When the slide is in the intermediate position shown in Fig. 6, the cam member is moved thereby into the neutral or intermediate position there shown so that neither cam face *j²* or *j³* can be acted upon by said cam *g*. When said slide occupies a position at one 90 extreme of its movement, as in Fig. 5, the cam member will by the links *i*, *i*, be moved so that one cam face lies upon the corresponding pin *k* and the other cam face is brought into operative relation to the cam *g*. In the rotation of said cam *g* the point thereof engages the cam face *j²* of the cam member and swings the latter in a vertical plane, the opposite end resting or pivoting upon the corresponding pin *k*. The slot in the 100 link *i* permits the proper swinging movement of said link, in accordance with the described lifting movement of that end of the cam member to which it is attached, the link attached to the other end of the cam member 105 being substantially held from movement by a pin *h⁴* upon the slide. When said slide is moved to its limit in the opposite direction the position of the cam member and the links connecting the same will be reversed from the position shown in Fig. 5, so that the cam face *j³* will be brought into operative relation with the cam *g* and the cam face *j²* will rest upon its pin *k*. Near the opposite ends of said cam member are attached the links *l*, *l*, connected at their upper ends to arms *l'*, *l'*, pinned upon studs *l²*, *l²*, whereon are also pinned pawls *l³*, *l³*, adapted in their inactive position to lie with their points beneath the axes of the 110 115 120 125 130

corresponding ratchet wheels l^8 , l^8 , and out of contact with the teeth thereof. Loosely connected with said studs are levers l^4 , l^4 , which are pivoted co-axially with the respective ratchet wheels and are adapted to be held in close frictional engagement with the faces thereof by the coil springs l^6 , l^6 , mounted upon the bolts l^9 , l^9 . Upon the lower faces of said levers l^4 , l^4 , near their pivotal points, are ears l^6 , l^6 , having set screws l^7 , l^7 , engaging the arms l' , l' , near their inner ends. In the rotation of the cam g the point thereof acting upon that cam face of the cam member which has been brought into operative relation thereto by the movement of the slide, will thereby raise the corresponding link l , which will swing its arm l' about its stud l^2 thereby bringing the pawl l^3 into engagement with the teeth of the ratchet l^8 . The continued upward movement of the link will swing the lever l^4 about its pivot, (such movement being hitherto prevented by the spring l^5) and thereby the pawl will advance its ratchet the proper distance. As the weight of the parts tends to keep the operative face of the cam member in engagement with the pointed cam g , when the point of said cam shall have passed from engagement with the operative cam face, the link l will be moved downward, thereby bringing the lower edge of the arm l' in engagement with the set screw l^7 , and carrying with it the pawl. In the further downward movement of the link the arm l' will carry with it the lever l^4 , thus bringing said pawl into its normally inactive position.

Rotatably mounted in the upper portion of the standards a' , a' , upon arms s , s , is a rod s' . That arm s mounted in the standard a' to which the ratchets are adjacent, is extended below its pivot, as shown in Fig. 4, and at its lower end has mounted a sprocket wheel s^2 and a co-axial gear wheel s^3 , shown in dotted lines in said figure. Upon the rod s' , and in vertical alinement with the sprocket wheel s^2 , is a sprocket wheel s^4 mounted for rotation, said sprocket wheels s^3 and s^4 being operatively connected by a sprocket chain s^5 . By manually shifting the rod s' toward the front or rear of the machine the gear s^3 may be brought into engagement with either gear wheel s^6 mounted co-axially with the respective ratchets l^8 , l^8 , to rotate therewith. The gear sprocket wheel s^4 is under the manual control of the operative, being turned by rotation of rod s' , and when the gear s^3 has been thrown into engagement with either gear s^6 the corresponding ratchet may be given partial movement of rotation so that the position of either set of warp threads with relation to the other may be altered by lengthwise movement of the holder or carriage whereon the same is mounted. In other words, there is thus provided manual compensating

means that may be brought into operative relation to either set of warp threads.

The ratchets l^8 , l^8 , are mounted upon studs in the upper end of one of the standards a' , at one face thereof. Upon the opposite face, 70 and co-axially with the ratchets, are mounted the worm wheels l^9 , l^9 , adapted to engage the teeth l^{10} , l^{10} , formed upon the overhead hanger rods b^5 , b^5 , of the warp holders or carriages. It will thus be seen that the action of the cam g is through the described mechanism longitudinally to adjust either warp holder or carriage, the warp holder or carriage which is thus under the control of said cam g depending upon the position of 80 the slide h .

The warp uniting carriage A, shown more clearly in Fig. 1, has standards m , m' , rising from the base thereof. Mounted in the upper end of said standard m is a shaft m^2 85 adapted to receive a movement of rotation by a pinion m^3 and carrying at its opposite end a segmental plate m^4 , forming one element of the warp twisting member, said plate being adapted in the partial movement 90 of rotation of the shaft m^2 to be brought into engagement with the opposing plate m^5 of the warp twisting member, said opposing plate being stationarily mounted upon an arm projecting from the warp carriage, as 95 shown in Fig. 2. Said movable member m^4 is provided with a thread cutting knife m^{4x} shown in dotted lines in said figure. Thus the corresponding threads of the two warps 100 are twisted together, said threads being brought into close relation with each other and in a position to be twisted together by the helical hook n when the end threads of the two warps are in position to be engaged thereby. Said hook n is mounted upon one 105 end of the shaft n' which is adapted to be rotated by the bevel gear n^2 , upon the opposite end of the shaft, and driven by the bevel gear n^3 upon the shaft n^4 , mounted in suitable hangers, and having at the lower end 110 a bevel wheel n^5 meshing with a similar wheel n^6 upon the drive shaft f . Upon said shaft n' is mounted a pinion o meshing with an intermediate pinion o' through which the desired movement of partial rotation is 115 imparted to the pinion m^3 upon the shaft m^2 . The shaft m^2 passes through the upright m' upon the traveling carriage.

Mounted in the standards a' , a' , of the machine are the lease rods c , c' , and d , d' . 120 For each warp there are provided two lease rods, disposed in substantially vertical alinement, each being semi-cylindrical in cross section. The threads of the warp are leased as shown in Fig. 8 about said rods which are mounted with their curved faces oppositely disposed so that alternate threads of each warp pass from the curved face of one rod in a diagonal direction to and about the 125 curved face of the other rod, crossing the 130

remaining threads of the warp which have an essentially true vertical position, owing to their engagement with the flat faces of said rods. Mounted upon the lease rods are 5 tubular sleeves r , r , having shoulders r' , r' , at their forward semi-tubular ends, the function of said shoulders being to maintain the body of the respective warp out of engagement with the helical hook n and out 10 of engagement with the warp twisting mechanism, permitting merely the end threads of the two warps to be at the proper time engaged by said hook and said uniting mechanism. Each sleeve, and preferably at or 15 near the forward end of its tubular portion, is pinned to a block r^5 as shown in Fig. 7, said block being semi-circular in cross section and having its flat face engaging the flat face of the corresponding semi-cylindrical lease rod, whereby each sleeve and its lease rod move in unison when a movement 20 of partial rotation is imparted to the sleeve. Viewing Fig. 8, it will be seen that the shoulders r' , r' , of a pair of lease rods are 25 oppositely disposed. A movement of semi-rotation imparted to the lease rods c , c' , and d , d' , and the sleeves r , r , will carry the shoulders r' , r' , out of engagement with the end thread of the warp, such as the thread 30 r^2 in Fig. 8, and will permit said thread (it being properly tensioned for that purpose) to snap or move into operative engagement with the helical hook and the warp twisting members. Such semi-rotation of the lease rods c , c' , and the sleeves r , r , will move the shoulders r' , r' , into engagement with what is now the end thread of the warp, being the thread r^3 shown in Fig. 8, so as to maintain the body of the warp in the position shown 40 in Fig. 1. The lease rods c , c' , are so mounted in the standards a , a' , that a movement of semi-rotation may be imparted to them by the described rotative movement of the sleeves r , r , which are given a longitudinal 45 movement thereon so as to maintain the body of the two warps well out of engagement with the hook n and the uniting members as shown in Fig. 1, but to permit the threads shown as deflected in said figure to 50 be brought into closer relation with said parts at the proper time, so that the end thread of each warp may be engaged by the hook and the uniting members. This described action of the shoulders r' , r' , upon 55 the warps whereby the same are intermittently pushed away from the uniting mechanism and are then returned into closer relation thereto is accomplished through the instrumentality of a cam p , mounted upon 60 the shaft n' , said cam having a cam track p' with which engages a projection p^2 upon a block p^3 connected to the sleeves r , r , so as to impart reciprocating movement thereto, said sleeves being guided in tubular supports 65 carried by a projection p^4 extending from

the upright m' . The block p^3 is guided in its movement upon the projection p^4 . The described movement of reciprocation of said sleeves is preferably so timed with regard to the movement of semi-rotation thereof, 70 that when the end threads of the two warps are permitted to snap past the shoulders thereon, the other threads of each warp stand in their normal vertical position. The movement of said sleeves to the left, however, viewing Fig. 1, deflects or pushes the warps, or a portion thereof, as already stated entirely clear of the helical hook and the twisting member. 75

The lease rods c , c' , d , d' , are given their described intermittent movement of semi-rotation by reason of pinions shown in dotted lines in Figs. 1 and 2, mounted upon the sleeves r , r , said pinions being driven in unison by a gear m^6 , shown in dotted lines 85 in Fig. 2. The pinion upon the sleeve for the lease rod d is intermittently moved by the star wheel m^7 to which movement is suitably imparted from the shaft n' . 80

It will be observed that the warp uniting 90 machine is adapted to hold or sustain therein the full width of the two warps supported in series as described so that the warp uniting mechanism, the specific embodiment of which is a warp twisting mechanism, may 95 act upon corresponding threads of successive pairs throughout the entire width of a cotton warp without any stoppage or delay such as would be occasioned in a construction wherein the machine could not accommodate the full width of the cotton warp but only sections thereof at a time, thus necessitating the application of successive sections of the warps to the machine before union of all the threads of the two warps is 100 completed. 105

Not only is the machine adapted for use without stopping or replenishing the same, to operate upon the full width of a cotton warp but it is also adapted for use upon any 110 wide warp, whether of silk, cotton or any other material. It is, of course, apparent that the machine is equally adapted for use upon narrow warps, such as, for instance, upon material to be used in narrow ware silk 115 looms. A peculiar advantage, however, of our mechanism is, as previously stated, that it is equally adapted for operation without delay or stoppage upon an entire cotton warp, or other wide warp, as distinguished 120 from what is known as a narrow ware warp. 125

In Fig. 10 is shown a locking means to hold the gear s^3 of the manual compensating means in engagement with the corresponding gear s^6 of either warp holder or carriage, or in an intermediate position out of mesh with either of said gears. Upon the arm s is provided, in a hole therein, a pin w' spring 130 pressed by the spring w^2 positioned between the end of the pin and the adjusting screw

w³. Upon the frame a' are three shallow sockets, w, with any one of which the rounded end of the pin may be engaged so as to hold the gear s² in any of its described positions. The sockets, w, are so shallow that side pressure upon the manual operating means at either end of the loom will be sufficient to release the locking means. Any other suitable locking means may be employed.

10 While we have shown one embodiment of our invention, we wish it to be clearly understood that we are in nowise to be limited to the mechanism shown and described, but to the mechanism shown and described, but

15 that

What we desire to claim is:—

1. In a warp uniting machine, means for holding a pair of leased warps, means for forcing away from the foremost thread of each warp the threads next adjacent thereto, uniting means adapted to engage and unite the pair of threads thus separated, and a support for said uniting means at one side of said warps sustaining the latter between the support and the end threads of the warps.

2. In a warp uniting machine, means for holding a pair of leased warps, means for forcing away from the foremost thread of each warp the threads next adjacent thereto, uniting means adapted to engage and unite the pair of threads thus separated, and a support for said uniting means at one side of said warps adapted to be fed toward the end threads of the warp during operation of the machine.

3. A warp uniting machine having means for holding a pair of leased warps, lease rods extending the length of the warp, means upon said lease rods but relatively movable thereto for separating the foremost threads of the two warps, and means for uniting the separated pair.

4. A warp uniting machine having means for holding a pair of leased warps, lease rods extending the length of the warp, means co-axial with the lease rods for separating the foremost threads of the two warps, and means for uniting the separated pair.

5. A machine for acting upon warp threads having means for holding a warp, a lease rod extending the entire length of the warp, means upon said lease rod but relatively movable thereto for separating the foremost thread of said warp, and means for operating upon said thread.

6. A machine for acting upon warp threads having means for holding a warp, a lease rod extending the length of the warp, means co-axial with said lease rod for separating the foremost thread of the warp, and means for operating upon such thread.

7. A warp uniting machine having means for holding a pair of warps, lease rods ex-

tending the entire length of each of said warps, thread twisting mechanism adapted to advance relatively to the warp threads, and means mounted upon the lease rods but relatively movable thereon for separating 70 the foremost threads of the warp and permitting their engagement by the twisting mechanism.

8. A warp uniting machine having means for holding a pair of warps, lease rods extending the length of each of said warps, thread twisting mechanism adapted to advance relatively to the warp threads, and means co-axial with the lease rods for separating the foremost threads of the warp and 80 permitting the engagement by the twisting mechanism.

9. In a machine for operating upon warp threads, an operating mechanism, means for holding a leased warp, and means movable 85 with the operating mechanism for separating the foremost threads of the warp, said means comprising a sleeve mounted upon each lease rod and movable lengthwise the same, each sleeve being provided with a rotatable shoulder for engaging alternately the threads on opposite sides of the lease rod.

10. In a machine for operating upon warp threads, an operating mechanism, means for holding a leased warp, and means movable 95 with the operating mechanism for separating the foremost threads of said warp, said means comprising a member mounted upon a lease rod and having rotative and longitudinal movement, and having means to 100 engage the warps.

11. A warp uniting machine having means for holding a pair of leased warps, means for separating the foremost threads thereof, and twisting means located between the 105 warps for twisting the separated threads while leaving the twisted ends still leased.

12. A warp uniting machine having means for holding a pair of leased warps, means for separating the foremost threads thereof, and uniting means located between the 110 warps for uniting the separated threads while leaving the united ends still leased.

13. A warp uniting machine having thread uniting means, relatively movable warp supports, means for controlling relative movement thereof and means for holding a pair of leased warps thereon.

14. A warp uniting machine having means for holding a pair of leased warps 120 and means for causing relative movement between said holders.

15. A warp uniting machine having means for holding a pair of leased warps, uniting means having a support relatively 125 movable to said warps, holding means and a plurality of rotary and reciprocating elements for separating the foremost threads of the leased warps from the next adjacent threads.

16. In a warp replenishing machine, means for leasing a warp comprising two leasing members, each of which has one substantially flat face whereby alternate threads 5 maintain an undeflected position.
17. In a warp replenishing machine, means for leasing a warp comprising two leasing members, each of which has one substantially flat face whereby alternate threads 10 maintain an undeflected position, and means for imparting rotative movement to said members.
18. A warp uniting machine having warp uniting mechanism and means for holding 15 leased the threads of a warp comprising two members, each having a substantially flat face in alinement with each other whereby alternate threads of the warp have an undeflected position.
19. A warp uniting machine having warp uniting mechanism and means for holding 20 leased the threads of a warp comprising two members, each having a substantially flat face in alinement with each other where- 25 by alternate threads of the warp have an undeflected position, and means for imparting rotative movement to said members.
20. A warp uniting machine having means for supporting two wide warps and 30 thread uniting means, a support therefor and means for deflecting the body of the warp in the plane thereof and away from the support for the uniting means.
21. In a machine for operating upon warp 35 threads, means for holding two warps in series, lease rods for said warps, means for operating upon corresponding threads of said warps in succession, means co-axial with said lease rods, and means for imparting movement to said co-axial means relatively 40 to said lease rods to permit corresponding threads of the two warps in succession to come within range with the operating means.
22. In a machine for uniting warp 45 threads, means for holding two warps in series, a uniting mechanism having movement relative to said warps, means for bringing corresponding threads of the two warps into 50 position to be operated upon by the uniting mechanism, lease rods for the warps, and means co-axial therewith and relatively movable thereto for releasing corresponding threads of the two warps in successive pairs 55 from the said series.
23. In a machine for uniting warp 60 threads, means for holding two warps in series, means for uniting corresponding threads of said warps in succession, said means having relative movement with respect to the warps, a helical hook having movement relative to said warps and adapted to present corresponding threads to the uniting mechanism, lease rods, and means 65 co-axial therewith for releasing correspond- 65 ing threads of said warps therefrom in successive pairs.
24. In a machine for operating upon warp threads, means for holding two warps in series, means for twisting together corresponding threads of said warps in successive pairs, said means having relative movement with respect to said warps, a helical hook having relative movement with respect to said warps, leasing means for said warps, 70 and means co-axial with said leasing means having movement longitudinally thereof for releasing corresponding threads of said warps therefrom in successive pairs.
25. In a machine for uniting warp 75 threads, means for holding two warps in series, means for twisting together corresponding threads thereof in successive pairs, said means having relative movement with respect to said warps, means for presenting 80 said corresponding threads to the twisting mechanism, leasing means for said warps, and means co-axial therewith but having longitudinal movement with respect thereto for releasing corresponding threads from 85 said warps in successive pairs.
26. In a machine for uniting warp 90 threads, means for holding two warps in series, means for twisting together corresponding threads of said warps in successive pairs, said means having relative movement with respect to said warps, means for presenting corresponding threads to said 95 twisting means, lease rods for said warps having capacity for rotative movement, 100 sleeves mounted thereon and having rotative movement therewith and longitudinal movement with respect thereto for releasing corresponding threads from said warps in successive pairs.
27. In a warp uniting machine, means for holding two warps in series, means for twisting together corresponding threads of said warps in successive pairs, means for presenting corresponding threads to said 110 twisting mechanism, rotative lease rods for said warps, sleeves mounted thereon, means for rotating said sleeves with said lease rods, means for reciprocating said sleeves on said lease rods, said sleeves having means at 115 their forward end for releasing corresponding threads from said warps in successive pairs.
28. In a machine for operating upon warp 120 threads, means for holding two warps in series, means for operating upon corresponding threads of said warps in successive pairs, said means having relative movement with respect to said warps, and means to cause relative compensating movement 125 between said warps and the operating mechanism, said means comprising a rotative cam, a cam member having two active

faces, means for bringing either face into operative relation with said rotative cam, and means connecting said cam member with each of said warp holding means.

5 29. In a warp uniting mechanism, means for holding two warps in series, warp uniting means having relative movement with respect to the warps to permit progressive advancing movement thereon, and means 10 automatically to cause relative compensating movement between the uniting mechanism and either series of warps, said means comprising a rotative cam, a cam member having two operative portions, means for bringing 15 either portion into coöperation with said rotative cam, and connections between said cam member and said means for holding the warps.

30. In a machine for uniting warp 20 threads, means for holding two warps in series, warp uniting mechanism adapted to operate upon corresponding threads in successive pairs, means automatically to cause relative compensating movement between 25 said holding means and said uniting means, said means comprising a rotative cam, a slide adapted for manual adjustment into operative or inoperative positions, means connected with said slide and adapted by the 30 movement thereof to be brought into operative or inoperative relation with respect to said rotative cam, and connections therefrom to said means for holding the warps.

31. In a machine for operating upon warp 35 threads, means for holding two warps in series, means for uniting corresponding threads thereof in successive pairs, said means having progressive relative movement with respect to said warps, means automatically to cause compensating movement 40 between said uniting mechanism and the threads of either warp, comprising a rotative cam, a member adapted to be brought into operative relation therewith, and connections from said member to each of said 45 warp holding means.

32. In a machine for uniting warp threads, means for holding two warps in series, means for twisting together corresponding threads thereof in successive pairs, 50 means for causing relative compensating movement between either of said warp holding means and said twisting means and comprising a rotative element, a slide, and 55 means controlling thereby to bring either warp holder into coöoperative relation with said rotative element.

33. In a machine for uniting warp threads, means for holding two warps in 60 series, means adapted to unite corresponding threads thereof in successive pairs, and means to cause automatically relative compensating movement between the uniting mechanism and either warp holding means,

and comprising a rotative element, a slide, 65 and means controlled thereby to bring either warp holder into coöoperative relation with said rotative element.

34. In a machine for uniting warp threads, means for holding two warps in 70 series, means adapted to unite corresponding threads of said warps in successive pairs, and means for causing relative compensating movement between the uniting mechanism and said warp holding means and comprising 75 a cam *g*, a slide *h*, mounted for movement transversely thereof, a cam member *j* having two operative faces, links *i*, *i*, connecting said member and said slide, and operative connections between said cam 80 member and said warp holding means and imparting longitudinal movement thereto.

35. In a warp uniting machine, the combination with means for supporting a pair of leased warps side by side, selecting means 85 working upon the lease of each warp for selecting successive threads therefrom, means for causing relative traverse between the warps and the selecting means, and means for automatically compensating the position 90 of each of said leased warps with reference to the selecting means.

36. In a warp uniting machine, the combination with means for supporting a leased warp, selecting means acting upon the lease, 95 means for causing relative traverse between the warps and the selecting means, and means for automatically compensating the position of the warp relatively to the selecting 100 means.

37. In a warp uniting machine the combination with a warp support, means for holding a warp in a leased condition thereon, a thread selecting means, a traversing carriage for the same, means for moving 105 said carriage with relation to the warp support and means for moving the warp support.

38. In a warp uniting machine the combination with a warp support, means for holding a warp in a leased condition thereon, a thread selecting means, a transversing carriage for the same, means for moving 110 said carriage with relation to the warp support, and means for automatically moving 115 the warp support.

39. In a warp uniting machine the combination with a warp support, means for holding a warp in a leased condition thereon, a thread selecting means, a traversing 120 carriage for the same, means for moving said carriage with relation to the warp support and means for manually moving the warp support during operation of the machine to compensate the position of the 125 foremost warp threads with relation to the selecting means.

40. In a warp uniting machine the com-

5 bination with two warp supporting members, means for holding a warp in a leased condition on each of said supports, a thread selecting member for acting upon both of the said warps; means to cause traversing movement of said thread selecting means with relation to one of said supports, and means for automatically adjusting the position of two of said members, with reference 10 to the third.

15 41. In a warp uniting machine the combination with means for supporting a leased warp, selecting means acting upon the lease, means for causing traverse of the selecting means with relation to the support, and means for manually compensating the position of the warp relative to the selecting means.

20 42. In a warp uniting machine the combination with means for supporting a leased warp, selecting means acting upon the lease, a traversing carriage for the same, means for moving said carriage to cause progressive action of the selecting means upon the 25 warp threads, and means for manually adjusting the position of the said leased warp.

30 43. A mechanism for joining together the ends of two leased warps and combining a pair of warp supports, means for holding each warp in leased condition upon its support, means for selecting a thread from each said warps, means for uniting said selected threads and means for moving one of the said warps with relation to the uniting 35 means and to the other warp.

40 44. In a warp uniting machine the combination with a pair of warp supports, separate ratchet and pawl feeding means for each of the said supports, and means for applying power to either of the said feeding means at will.

45 45. In a warp uniting machine, the combination with means for supporting a pair of warps in a leased condition, uniting mechanism, thread selecting mechanism, a carriage and operating mechanism on the carriage for the uniting and the thread-selecting mechanisms, said selecting mechanism being located within the lease and between the operating mechanism and the unseparated threads of the two warps which remain to be united.

50 46. In a warp uniting machine, the combination with means for supporting a pair of warps, means comprising a pair of leasing members for holding them in leased condition, means carried by the leasing members for separating the threads of the respective warps one by one, a carriage and operating means on said carriage for said separating means, said separating means being located between the operating means and the unseparated threads of the two warps which remain to be united.

55 47. In a thread separating and selecting

mechanism, the combination with means for holding the threads of a warp in leased condition, thread selecting means adapted to operate upon said leased warp, and means for compensatingly longitudinally adjusting 70 said warp relatively to the thread selecting means.

75 48. In a separating and selecting mechanism for warp threads, the combination with a warp support, means for holding the warp threads clamped therein, one or more lease rods for maintaining the threads in a leased condition, selecting means for selecting successive threads from the leased warp, and means for compensatingly adjusting the 80 frame longitudinally with reference to the thread selecting means.

85 49. In a thread separating or selecting mechanism, the combination with selecting means, means for holding the warp threads 85 in leased condition relatively to the selecting means, means to cause relative movement between the selecting means and the warp holding means, and means automatically to effect a compensating adjustment between 90 the warp and the selecting means.

95 50. In a thread separating and selecting mechanism, the combination with selecting means, means for holding the warp threads in leased condition relatively to the selecting means, means to cause relative movement between the selecting means and the warp holding means, and means manually to effect a compensating adjustment between the 100 warp and the selecting means.

105 51. In a machine for acting upon warp threads, the combination with a warp support, means for holding a warp in leased condition thereon, thread selecting means adapted to press against the foremost members of the unseparated body of threads alternately on opposite sides of the lease, means for causing relative traverse between the warp and the selecting means, and means for automatically adjusting the position of the warp support with relation to the selecting means during the operation of the machine to compensate the position of the foremost warp threads with relation to said selecting means.

110 52. In a machine for acting upon warp threads, the combination with a warp support, means for holding a warp in leased condition thereon, thread selecting means adapted to press against the foremost members of the unseparated body of threads, means for causing relative traverse between the warp and the selecting means, and means for automatically adjusting the position of the warp support with relation to the selecting means during the operation of the machine to compensate the position of the foremost warp threads with relation to said selecting means.

115 53. In a machine for uniting warp 130

threads, the combination with two warp supports, means for holding on each a warp in leased condition, thread selecting means adapted to press against the foremost members of the unseparated body of leased threads, means to cause traversing movement of said thread selecting means with relation to said supports, and means for automatically adjusting the position of one 5 of said supports with relation to said remaining support to compensate the position of the foremost warp threads with relation to said selecting means.

54. In a machine for uniting warp threads, the combination with two warp supports, means for holding on each a warp in leased condition, thread selecting means adapted to press against the foremost members of the unseparated body of threads, a 10

carriage for supporting said selecting means, 20 means to automatically impart a feeding movement to said carriage across said warps, and means for automatically and additionally adjusting from time to time the position of one warp support to compensate for 25 variations in alinement of the foremost warp threads on said support with relation to said selecting means and the foremost threads of the remaining warp.

In testimony whereof, we have signed our 30 names to this specification, in the presence of two subscribing witnesses.

CHARLES D. LANNING.
EDGAR F. HATHAWAY.
